United States Patent Office

Des. 208,381

Patented Aug. 22, 1967

208,381

TRAFFIC SIGNAL

Howard E. Miller, Douglas County Courthouse,
Tuscola, Ill. 61953

Original design application Oct. 15, 1965, Ser. No. 87,517,
now Patent No. 205,696, dated Sept. 6, 1966. Divided
and this application Aug. 1, 1966, Ser. No. 5,216

Term of patent 14 years

(Cl. D72—1)

FIG. 1 is a front elevational view of the traffic signal, showing my new design;

FIG. 2 is a side elevational view;

FIG. 3 is a back elevational view; and

FIG. 4 is a top plan view.

The broken line representation of a support pole in FIGS. 1, 2 and 3 is for purposes of illustration only.

This is a division of design application Ser. No. D.87,517, filed Oct. 15, 1965, now Design Patent No. D.205,696.

I claim:

The ornamental design for a traffic signal, as shown and described.
